UNITED STATES PATENT OFFICE.

OSCAR J. JOHNSON, OF CLOQUET, MINNESOTA.

WRENCH.

1,109,531.

Specification of Letters Patent.

Patented Sept. 1, 1914.

Application filed September 5, 1913. Serial No. 788,345.

To all whom it may concern:

Be it known that I, OSCAR J. JOHNSON, a subject of the King of Sweden, residing at Cloquet, in the county of Carlton and State of Minnesota, have invented certain new and useful Improvements in Wrenches, of which the following is a specification.

A disadvantage incidental to the use of wrenches heretofore proposed of the type 10 employing a movable jaw adjustable toward a fixed jaw, and fixed at adjustments by co-operating rack and catch means, resides in the fact that a required nicety of adjustment of the jaw is often not obtainable 15 owing to the spacing of the teeth of the rack necessitating a positioning of the jaw at a point at which its gripping action is not wholly effective. It is with the aim of obviating inefficient operation of the said class 20 of wrenches that the following described improvements have been evolved, the same embodying essentially the utilization of a specially designed rack on the wrench shank engageable by alternately acting holding 25 catches, according to the particular adjustment required for the movable jaw.

With the foregoing and other objects in view the details of the invention will be understood on referring to the description supplied hereinafter and to the accompanying drawings, in which—

Figure 1 is a side elevation of a wrench embodying the invention; Fig. 2 is a front view of the same; and Fig. 3 is a transverse 30 section taken about on the line 3—3 of Fig. 2.

The wrench of the present invention comprises the usual main parts, namely the shank 1 having the handle 3 at one end and provided with the jaw 2 at its opposite end, 40 a sliding jaw 4 being movable longitudinally of said shank intermediate the parts 2 and 3. Formed lengthwise of the shank 1 are the racks 1^a, the teeth and notches of each of which are staggered with respect to 45 those of the other. The sliding jaw 4 is formed with an offstanding arm 5 which is supplied with openings in which sliding catches or plungers 6 are mounted. The catches 6 extend from the point of their support upon the arm 5 through openings in a side of the hollow shank receiving portion of the jaw 4 and each catch is adapted to engage with an adjacent one of the racks 1^a.

Mounted on the outer extremity of the 55 arm 5 is a small finger manipulating lever 8 having laterally extending projections 8^a

which pass through slots in the outer ends of the catches 6. Coiled springs surround the catches 6 intermediate the outer portion of the arm 5 and the body of the jaw 4 and normally tend to project the catches into engagement with their respective racks. The lever 8 is pivotally supported on the arm 5 by the pivot member 9 and with the foregoing construction of the various parts 60 in view the operation of the invention to be now set forth will be clearly understood.

Assuming that the jaw 2 of the tool has been engaged with the work, by depressing the outer end of the lever 8 the catches 6 will 70 both be in disengaged relation to their racks 1^a, thereby permitting the jaw 4 to be moved freely to the work. Owing to the staggered relation of the teeth of the racks 1^a, practically at any point at which the jaw 4 is 75 positioned upon engaging the work, one or the other of the catches 6 will be opposite a notch located between the teeth of its rack 1^a so that on releasing the lever 8 such catch may engage the opposite notch and lock the 80 jaw 4 at the required adjustment. The catches 6 are adapted to move independently of one another owing to the provision of the slots therein through which the projections 8^a of the lever 8 pass. As seen in Fig. 85 1 and also in Fig. 3 one of the catches 6 is holding the jaw 4 at an adjustment while the other catch is inactive for this purpose. The means employed for securing the desired adjustment of the wrench in engaging 90 the same with the work, is very simple according to the embodiment of this invention and affords many advantages from a practical standpoint which will be obvious having in view the above explanation of structure 95 and operation of the wrench parts.

Having thus described the invention, what is claimed as new is:

1. A wrench comprising a shank having a stationary jaw and provided lengthwise thereof with racks arranged in staggered relation, a jaw movable along the shank and having an offstanding arm provided with openings therein, spring-pressed pins slidably mounted in the openings of said arm and adapted at their inner ends to engage with the racks of the shank, the said pins being formed with longitudinal slots at their outer ends, springs arranged between said arm and the body of the movable jaw and acting on the catches to cause engagement of the latter with the racks, a lever pivoted 100 105 110

to the arm aforesaid, and means on the lever engaging in the slots of said pins for operating the pins substantially as specified.

2. A wrench comprising a shank having a stationary jaw and provided lengthwise thereof with adjacent racks arranged in staggered relation, a movable jaw adjustable on the shank, a pair of independent spring-pressed reciprocatory plungers mounted side by side on said movable jaw and arranged at their inner ends to engage said racks, said movable jaw having a guide arm common to said plungers for guiding the movement of

the same, an operating lever pivoted to the movable jaw, pin and slot connections intermediate said operating lever and the outer ends of the plunger permitting movement of one plunger independently of the other plunger, and a handle carried by the shank.

In testimony whereof I affix my signature 20 in presence of two witnesses.

OSCAR J. JOHNSON.
